UNITED STATES PATENT OFFICE.

WILL C. NEAHR, OF DENVER, COLORADO, ASSIGNOR TO THE PROTECTIVE SIGNAL
MANUFACTURING COMPANY, OF DENVER, COLORADO, A CORPORATION.

CIRCUIT-CLOSER.

1,134,547.

Specification of Letters Patent.

Patented Apr. 6, 1915.

Application filed July 31, 1912. Serial No. 712,511.

To all whom it may concern:

Be it known that I, WILL C. NEAHR, a citizen of the United States, residing at Denver, in the county of Denver and State of Colorado, have invented certain new and useful Improvements in Circuit-Closers, of which the following is a specification.

This invention relates to improvements in circuit closers and its principal object is to provide an instrument of this class which is constructed to close a circuit by the vibrating motion imparted to one of its contact members by a movement of the support to which the instrument is attached, and which is provided with electro-magnetic means by which the said members are continuously maintained in engagement until the circuit of which they are terminals, is opened at another point.

While my invention may be employed in connection with electric systems of different character, it is more particularly adapted for use in alarm systems such as are used at railroad crossing to announce the approach 25 of a train in which case the circuit closer is suspended from a rail of the railroad track at a distance from the crossing, and connected in an electric circuit with an alarm and a therewith electrically associated automatic switch which is actuated by the completion of the circuit in which the circuit closing instrument is connected and which by current supplied through a local circuit connects the alarm in the first mentioned 35 circuit during a period determined by a cycle of intermittent movements, at the termination of which the normal condition of the parts is automatically restored.

While the switch above referred to may be of any construction suitable to accomplish the purpose of causing the operation of an alarm or other electric instrument, during a determinate period after the circuit has been reopened at the point at which the circuit closer is connected therein, I preferably employ the mechanism which in my co-pending application No. 712,512 has been shown in a system of electrical connections with the circuit closer which forms the sub-

ject of the present application and an electric alarm of ordinary construction.

In the drawings in the various views of which like parts are similarly designated. Figure 1 represents a plan view of the circuit closing mechanism, the casing in which it is inclosed having been shown in section, Fig. 2, a side elevation of the mechanism with the casing shown in section, Fig. 3, a section taken along the line 3—3, Fig. 1 drawn to an enlarged scale, Fig. 4, an enlarged section taken along the line 4—4, Fig. 1, and Fig. 5, a fragmentary view showing a modified construction of the device.

Referring to the drawings my improved circuit closing instrument consists of a casing 2 having at one of its ends an opening which is normally closed by a head 3 to which the operating parts of the instrument are attached. This head is fastened to the casing by means of screws 4 so that if at any time it is desired to inspect the circuit closing mechanism, the same may be withdrawn from the casing in its entirety by merely loosening the screws and removing the head.

The casing is provided at its upper surface with a pair of clamping devices 5 by means of which it is suspended from the foot of the rail 6 of a railroad track and a hood 7 is placed around its end closed by the head 3, to protect the binding screws and connections disposed exteriorly thereof.

The circuit closing mechanism proper consists of a bar 8 which is rigidly attached at one of its ends to the head 3 in insulated relation thereto and which at its free end has a slotted, upturned portion 29 which provides a stop to limit the movement of the vibrating element of the instrument, as will hereinafter be more fully described.

The bar 8 is attached to the head by means of screws 9 which extending through registering openings in the head and in a plate 10 placed exteriorly in insulated relation to the same, are fastened in threaded apertures of a plate 12 formed integral with the bar.

A binding screw 13 fastened in an aperture of the exteriorly disposed plate 10 ex-

tends through an opening in the head 3 lined with a bushing of non-conductive material and it is projected into an aperture in the plate 12 of the bar 8 to place the latter in electric communication with a conductor 14 fastened to the screw 13 at the outside of the casing. The openings in the head through which the screws 9 extend are likewise lined with bushings of insulated material so that the electric current flowing from the conductor 14 to the bar 8 can in no way reach the head or the casing to which the latter is connected.

Vertically adjustably disposed upon the bar adjacent the plate 12, is a clamping device which consists of two members 15 and 16 which are connected by screws 17 to clampingly secure an end of the vibrating element placed between them. The end of the device nearest the head is held in place by means of screws 18 which are secured in an enlargement of the bar 8 and which extend through registering holes in the two members, which are of greater diameter than the screws to allow of a limited pivotal movement of the device when it is being adjusted to vary the position of the vibrating element. This adjustment is accomplished by means of nuts screwed above and below the opposite end of the member 15 of the device upon bolts 19 which are secured to the bar 8 and extend loosely through openings in the end of the said member.

The vibrating element hereinbefore referred to consists of a flat spring 20 which at one of its ends is clamped between the members 15 and 16 and which at its opposite end carries a rigid iron rod 21 whose outer extremity extends loosely through the slot in the upturned portion 29 of the bar 8.

Secured upon the rod 21 is the spool of an electro-magnetic coil 22 which at one of its ends connects with a binding screw 23 extending through an opening in the head 3 in insulated relation to the same, and at its opposite end, with a contact-ring 24 of hardened steel which is insulated from the bar by means of an interposed bushing 31 of non-conductive material.

A contact screw 25 is vertically adjustably suspended above the contact ring 24 from the end of a rocker arm 26 which is pivoted in a groove in the upper end of the upturned portion 29 of the supporting bar and which at its opposite end is supported upon a coiled spring 27 placed in a recess in the bottom of the said slot.

The end of the rod 21 projecting beyond the magnetic coil is surrounded by a sleeve 28 made of brass or other magnetically transparent material which, during upward movement of the vibrating element, engages the upper end of the slot in the upturned portion of the bar.

The instrument is connected in an electric circuit by means of the binding screws 23 and 13 to which conductors 30 and 14 at opposite sides of the circuit, are attached. The binding screw 13, is, as hereinbefore explained, electrically connected with the conductive bar 8, and the other binding screw, 23, is by means of a wire which includes the windings of the magnet-coil, connected with the insulated ring 24. When in the operation of the instrument, the equilibrium of the vibrating element is disturbed, the consequent engagement of the ring 24 with the contact screw on the bar 8 closes the circuit and at the same time energizes the magnet. The magnetization of the core 21 of the magnet, causes it to adhere to the part of the conductive bar 8 to which it is adjacent when the circuit is completed through the contact between the ring 24 and the screw 25, and to thereby maintain the vibrative element in the position in which it closes the circuit, until the latter is broken at another point when the magnet is deenergized and the vibrating element is permitted to return to its normal position.

In the construction shown in the drawings, the conductive part of the instrument which is approached by the magnet-core when the vibrative element is in its circuit closing position, is the end of the slot in the upturned portion 29 of the bar 8, into which the rod 21 loosely extends.

The brass sleeve 28 around the end of the rod 21 is provided to prevent it "freezing" against the end of the slot in the piece 29 by the permanent magnetism of the parts after the magnet is deenergized, as would occur in case the iron core came in direct contact with the iron end portion of the bar.

The purpose of the resilient support 27 for the rocker arm 26 is to insure a positive conductive contact between the end of the screw 25 and the ring 24, which latter is provided with a contact point to engage with the point of the screw.

While for reasons of simplicity of construction and positiveness of action the arrangement of the parts of the circuit closing instrument as above described, are preferable, the magnetic-coil may be disposed separate from the vibrating element as has been shown in Fig. 5 of the drawings in which the magnet 50 is mounted upon the fixed supporting bar 8 in connection with a contact blade 51 which is fastened upon the same bar in insulated relation thereto. The vibrating element carries in this case, a contact 52 which is disposed to engage the blade 51 during its vibrating movement and the vibrative element and the magnet coil 125 are connected in the main circuit, as in the construction hereinbefore described.

Having thus described my invention what

- I claim and desire to secure by Letters-Patent is:
1. In a circuit closing instrument, a support having at one of its ends, an integral stop, a vibrative element mounted at one of its ends on said support, its opposite end being disposed to approach said stop during its movement in one direction, an insulated contact and a magnetic coil on said element connected in one side of a normally open electric circuit the opposite side of which is connected with said support, and a contact in electrical connection with said support and disposed to be engaged by the first mentioned contact during movement of the said element in the said direction.
  2. In a circuit closing instrument, a support having a fixed upturned, slotted terminal portion, a vibrative element mounted on said support and guided in said slot, a contact carried on said element and connected at one side of a break in an electric circuit, and a contact mounted on the said upturned portion to be engaged by the first-mentioned contact during movement of the said element in one direction, and connected at the opposite side of the break in the said circuit.
  3. In a circuit closing instrument, a support having a fixed upturned, slotted terminal portion, a vibrative element mounted on said support and guided in said slot, a contact carried on said element and connected at one side of a break in an electric circuit, and a contact resiliently mounted on the said upturned portion to be engaged by the first-mentioned contact during movement of the said element in one direction, and connected at the opposite side of the break in the said circuit.
  4. In a circuit closing instrument, a support having a fixed upturned, slotted terminal portion, a vibrative element mounted on said support and guided in said slot, a contact carried on said element and connected at one side of a break in an electric circuit, an arm mounted on the said upturned portion and an adjustable contact screw on said arm disposed to be engaged by the said contact during movement of the said element in one direction and connected at the opposite side of the break in the said circuit.
  5. In a circuit closing instrument, a vibrative element, a contact carried thereon, a second contact disposed to be engaged by the first-mentioned contact during movement of said element in one direction, said contacts being connected at opposite sides of a break in an electric circuit, and an electro-magnet the windings of which are connected in a side of said circuit and the core of which is carried on said element, a magnetic part of the instrument being disposed

to be approached by the said core during 65 said movement of the element, for maintaining the latter in the position in which it closes the circuit by the engagement of the contacts.

6. In a circuit closing instrument, a vibrative element, a contact carried thereon, a second contact disposed to be engaged by the first-mentioned contact during movement of said element in one direction, said contacts being connected at opposite sides of a break 70 in an electric circuit, and an electro-magnet the windings of which are connected in a side of the circuit and the core of which is disposed with relation to a magnetic part of the instrument to be brought by said 75 movement of the element, in operative adjacency to said part for maintaining the element in the position in which it closes the circuit by the engagement of the contacts.

7. In a circuit closing instrument, a vibrative element, a pair of normally separated contacts at opposite sides of a break in an electric circuit, adapted to be brought in engagement by movement of said element in one direction, and an electro-magnet carried 80 on said element, its windings being connected in a side of the circuit, the said instrument having a magnetic stop disposed to be approached by the core of the magnet during said movement of the element for maintaining the latter in the position in which 85 it closes the circuit by the engagement of the contacts.

8. In a circuit closing instrument, a vibrative element, an insulated contact carried 100 thereon, a second contact disposed to be engaged by the first-mentioned contact during movement of said element in one direction, said contacts being connected at opposite sides of a break in an electric circuit, and an 105 electro-magnet carried on said element, its windings being connected in a side of the circuit, the said instrument having a magnetic stop disposed to be approached by the core of the magnet during said movement of the element for maintaining the latter in the position in which 110 it closes the circuit by the engagement of the contacts.

9. In a circuit closing instrument, a vibrative element, an insulated contact carried 115 thereon and connected in one side of a normally open electric circuit, a magnetic coil of which said element is the core connected in the same side of said circuit, a stop adapted to be approached by said element 120 during its movement in one direction and connected in the opposite side of the said circuit, and a contact disposed to be engaged by the first mentioned contact during movement of the said element in the said 125 direction and electrically connected with the said stop.

10. A circuit closing instrument compris-

ing a vibrative element, a pair of contacts at opposite sides of a break in an electric circuit, disposed to be brought in engagement by movement of said element in one direction, and an electro-magnet the windings of which are connected in a side of the circuit, and the core of which is so disposed with relation to a magnetic part of the instrument as to be brought by said movement of the element, in operative adjacency

to said part for maintaining the element in the position in which it closes the circuit by engagement of the contacts.

In testimony whereof I have affixed my signature in presence of two witnesses.
